[57] CLAIM

The ornamental design for a taco plate, substantially as shown and described.

DESCRIPTION

FIG. 1 is a top, front perspective view of a taco plate showing our new design;

FIG. 2 is a top plan view thereof;

FIG. 3 is a bottom plan view thereof;

FIG. 4 is a right side elevational view thereof;

FIG. 5 is a left side elevational view thereof, which is a mirror image of the right side elevational view;

FIG. 6 is a front elevational view thereof, the rear elevational view being a mirror image of the front elevational view.
